SKIMMING DEVICE

Thomas W. F. Foster, Temple City, Calif., assignor to The Permanente Metals Corporation, Oakland, Calif., a corporation of Delaware

Application June 30, 1945, Serial No. 602,581

5 Claims. (Cl. 22—134)

1

This invention relates to the casting of magnesium and more particularly to the step of pouring molten magnesium into molds.

Magnesium castings made merely by pouring molten magnesium into molds and allowing it to cool therein without taking further precautions, generally have undesired characteristics. With present practice it is often difficult or impossible to obtain castings with the desired absence of included oxides, oxide skins, dross and slag. The cooled or solidified product having these included oxides, oxide skins, dross and slag not being homogeneous and being stratified or at least different at different parts thereof is a product of undesirable and inferior quality. It has been found that where a proper separation of these oxides, oxide skins, dross and slag is accomplished and, as far as possible, eliminating all turbulence in the metal as it enters the mold and having the flow as even as possible it is possible to obtain a more desirable product. Other difficulties in casting molten magnesium are due to the low specific gravity of the magnesium, which can result in slag and other materials which are to be excluded from the casting not floating in nor on the metal but sinking therein, and they can enter the casting as a result. Some attempts have been made to exclude the heavier substances, which have resulted in increasing the turbulence. An object of this invention is to minimize turbulence as the metal enters the mold and thereby minimize the disadvantages referred to above as being due thereto.

Another object of the invention is to separate from the metal entering the mold, foreign matter that is heavier than the molten magnesium.

Further objects of the invention are to provide a simple and economical device that can be used in connection with conventional magnesium foundry equipment, either in addition thereto or built in as an integral part thereof.

Still further objects will be apparent on reading this specification in connection with the accompanying drawings.

On such drawings:

Fig. 1 is a vertical section of a casting assembly which includes the novel skimming fixture; and

Fig. 2 is a perspective view of a modification of such fixture.

The invention can be used in connection with a conventional sand or other type of mold 11 having the customary down sprue 12 through which the molten metal enters the mold. The latter is shown as broken away since special fea-

2

tures of the mold itself, which may be conventional or as desired, form no part of this invention. A pouring basin 13 which may be round, angular, or in fact of any preferred shape, and made of sheet steel or of any other suitable material, is located over the down sprue to feed the molten metal thereto.

A skimming device 14 is placed within the pouring basin, covering the whole portion, 16, of the basin bottom area adjacent the down sprue, but not covering a very substantial portion, 17, of such bottom area. The fixture may comprise a top wall 18 above and spaced from the basin bottom, and end wall 19, and side walls 21, the end and side walls supporting the wall 18. A transverse slot 22 is provided at a level above the basin bottom, this being preferably in the top wall.

The molten metal is poured from the source of supply 23 into the space over the bottom area 17 and the level rises as pouring continues until it is higher than the top of the skimming fixture. The metal then flows horizontally from the pouring space to and through the slot 22.

It should be poured at least as fast as it flows through the slot, in order to maintain a head of metal thereover so that any floating oxide and/or oxide skin will be prevented from passing therethrough. Substances which are heavier than the molten metal and which may be present will be sunk to, and remain at, the bottom of the pouring space 17 outside of the skimming device.

The device may have any desired shape, the only requirement with respect thereto being that the inlet opening 22 be at a higher level than the bottom of the space 17 into which the metal is poured, and the metal be prevented from entering into the space within the skimming device except through such inlet. It may be made of baked core sand (Fig. 1), sheet metal (Fig. 2), or any other suitable material.

The invention is well adapted for use in pouring molten magnesium or other light metal in the presence of material heavy enough to sink therein. It is particularly well adapted for pouring magnesium which solidifies rapidly and which should be poured at a constant rate. This has heretofore required a high degree of skill on the part of the workman, and difficulties have been encountered even by those highly skilled. The invention automatically makes the rate of entry of the molten magnesium into the mold practically constant so that less skilled workmen can do the casting. It is also useful with certain metals where all of the material which it is desired to exclude from the mold floats.

Certain details have been illustrated and described for the purpose of explaining the invention without limiting it, and can be changed without departing from the spirit of the invention, the scope of which is defined in the appended claims. Although the invention is particularly adapted for use in the casting of magnesium it is to be understood that it may also be used in the casting of other metals and materials having floating slags, including brass, bronzes, ferrous metals and the like.

What is claimed is:

1. A movable pouring basin comprising an enclosed wall portion, and a skimming device disposed within said basin and comprising a top wall portion spaced above the bottom of said basin and provided with an inlet perforation and side walls supporting said top wall portion and cooperating with a part of said enclosed basin wall portion to form an open-bottom enclosure.

2. A movable, open-bottom pouring basin comprising a walled enclosure, and a skimming device disposed within said basin and comprising a top wall provided with an inlet perforation and spaced intermediate the top and bottom of the basin wall and side walls supporting said top wall and cooperating therewith to form an open-bottom enclosure.

3. A movable, open-bottom pouring basin comprising a continuous enclosed wall portion of uniform height and even bottom edges, and a skimming device disposed within said basin and comprising a top wall portion spaced up from the bottom edges of said pouring basin, said top wall portion being provided with a slot adapted to pass molten metal from said basin downward, and side walls supporting said top wall and cooperating therewith and a portion of said basin wall to form an open-bottom enclosure.

4. In a movable skimming device adapted to separate solid material from molten material being fed into the inlet sprue of a mold, a pouring basin comprising a walled enclosure, and a skimming device disposed within said enclosure and comprising a top wall intermediate the top and bottom of the pouring basin, said top wall being provided with an opening adapted to pass molten material from the pouring basin to the inlet sprue of the mold, and side walls supporting said top wall and cooperating therewith to form an open-bottom enclosure.

5. In a movable skimming device adapted to separate solid material from molten metal being poured into the inlet sprue of a mold, a movable open-bottom pouring basin comprising a continuous enclosed wall portion of uniform height and level bottom edges, and a skimming device disposed within said basin and comprising a top wall portion spaced up from the bottom edges of said pouring basin, said top wall portion being provided with a slot adapted to pass molten metal from said basin downward to said inlet sprue, and side walls supporting said top wall and cooperating therewith to form an open-bottom enclosure.
